UNITED STATES PATENT OFFICE.

JOHN HUNTER CASSIDY, OF MONTREAL, QUEBEC, CANADA.

LIFE-SAVING SUIT.

1,271,017.

Specification of Letters Patent.

Patented July 2, 1918.

Application filed September 28, 1915, Serial No. 53,034. Renewed November 24, 1917. Serial No. 203,867.

To all whom it may concern:

Be it known that I, JOHN HUNTER CASSIDY, a citizen of the Dominion of Canada, and resident of the city of Montreal, in the 5 Province of Quebec and Dominion of Canada, have invented certain new and useful Improvements in Life-Saving Suits, of which the following is a full, clear, and exact description.

10 This invention relates to improvements in life saving suits, and the object is to provide a waterproof buoyant suit which may be very quickly and easily put on in the event of a marine disaster, or which may be 15 worn by a person venturing on hazardous marine expeditions.

A further object is to provide a suit of this character which is particularly adapted to maintain the wearer as warm and dry as 20 possible.

A still further object is to provide a suit which may be readily adjustable to the body of the wearer, so as to impart a maximum of safety and comfort.

25 Still another object is to provide means for the escape of air and body moisture from the suit while it is being worn.

Another object is to provide a suit having a buoyant portion which may be detached 30 and worn separately.

To accomplish these objects, I provide a suit of waterproof material which completely envelopes the wearer's body, with the exception of the face. The upper portion of 35 the suit may be double walled, and between the walls thereof, buoyant material of very low specific gravity is disposed to insure flotation, or the buoyant material may be separate and detachable. The feet of the 40 device are preferably weighted with some material of high specific gravity, such as lead, so as to insure the wearer an upright position in the water. The arms of the suit are closed at the ends and divided into three 45 parts, one forming an inclosure for the wearer's thumb, a second for the index finger and a third for the remaining three fingers, thus providing an arrangement which allows ordinary use of the fingers 50 combined with a considerable degree of protection from the cold. The hood is also double walled on the top, sides and back to form an air space and give the wearer protection from the sun. In order to adapt 55 the suit to various sizes of people, a belt is

provided which may be tightened around the waist to hold the buoyant material down in its proper place. In order to assist the belt in this and positively guard against upward pressure of the buoyant material 60 choking the wearer, an adjustable strap is provided extending between the wearer's legs and connected to the belt at front and back, and operating to positively hold the belt and upper part of the device in proper 65 position. In order to facilitate the use of the hands and feet, the device is provided at the wrists and ankles with means for tightening the garment to accurately fit 70 the wearer.

In the drawings which illustrate the invention:—

Figure 1 is a perspective view of the suit as worn.

Fig. 2 is a vertical sectional view through 75 one leg and the body of the suit.

Fig. 3 is a front elevation of the empty suit.

Fig. 4 is a fragmentary view of one foot showing the means for adjusting the same 80 to the wearer's comfort.

Fig. 5 is a sectional view of the hand portion of the suit showing the automatic adjusting means.

Fig. 6 is a fragmentary sectional view 85 showing a slightly modified disposition of the float.

Referring more particularly to the drawings, 11 designates the body portion, 12 the legs, 13 the arms, and 14 the hood, of a suit 90 of waterproof material formed in one piece, and arranged to completely cover the wearer's body, with the exception of the face. The suit is dimensioned to give ample room for very tall or very stout persons, 95 and also to permit a person fully clothed to put on the suit in a minimum of time without the necessity of removing clothing or boots. The entire width of the suit is open at the shoulders, as shown at 15, in 100 Fig. 3, so that it may be gotten into without difficulty. The material around the opening is provided with a suitably arranged draw string 16, so that when a person is once in the suit, they may by pulling on the 105 string, draw the garment tight around the neck to prevent the entrance of water. The hood 14 is attached to the back of the suit, and is provided with an elastic insert in the neck, so that when the hood is drawn over 110

the wearer's head, the insert will tighten around the neck over the upper edge of the suit, and aid in excluding the water. For the same purpose the edge of the face opening 17 is provided with elastic reinforcement to draw the material tightly around the wearer's face. It will of course be understood that, if desired, draw strings may be used in both of these locations to 5
10 place the elastic inserts, but this is not thought desirable, as these drawing strings require manipulation, while the elastic inserts are automatic in their action. The body portion of the suit is provided with
15 an inner wall 18 extending from approximately neck to waist, and forming with the material of the suit a pocket or chamber 19 in which bodies of suitable buoyant material may be placed. This material may be
20 cork, light waterproof vegetable fiber, such as is used in making floating boat cushions, or may be hollow receptacles of rubber, metal or other suitable material. In the breast of the suit, a pocket is formed for the
25 reception of a stimulant or food receptacle 21, from which the food may be drawn into the wearer's mouth through a tube 22.

The feet or boots 23 are provided with heavy soles 24, such as sheets of lead or the
30 like which will insure the wearer a vertical position in the water. Owing to the looseness of the suit, it is necessary to provide for an approximately good fit of the boots when the suit is worn, in case it becomes
35 necessary for the wearer to walk on deck or wade ashore. For this purpose, the outer side of each ankle is provided with coöperating fastening devices 25 similar to those used on overshoes, or of any other desirable
40 pattern, by means of which the ankle portions or boot tops may be adjusted to fit closely around the wearer's ankles, and thus hold the boots rigidly in position. The same necessity prevails with respect to the
45 hand or glove portions 26 of the suit. As the clasps would be considerably in the way on the wearer's wrists, and would moreover be difficult to fasten, it has been found desirable to provide an elastic insert 27 in the
50 wrists of the suit, which will be expanded when the wearer's hand passes through, and will then close around the wrist and hold the glove portions 26 firmly in position. It will be understood that this arrangement of
55 both the body and the glove is necessary as the arm and leg lengths of the suit must be made sufficiently large to accommodate long-armed and long-legged persons, so that if a short-armed or short-legged person wore the
60 suit, the gloves and boots would be out of place on the hands and feet much of the time, unless retained. A further advantage of this arrangement is that all the fullness due to extra length is maintained in the
65 actual arms and legs, so that great freedom

of movement is permitted. The glove or hand portions 26 are divided into three parts, designated 26^a, 26^b and 26^c, for the respective reception of the thumb, index finger and remaining three fingers, thus providing all freedom necessary for manipulating the suit, and at the same time providing a maximum of warmth possible in conjunction with freedom of movement. 70

It is obvious that on small people, the 75 fullness or additional leg length might permit the buoyant bodies 20 to rise so high that they would seriously inconvenience the wearer, and possibly by pressing up at the neck have a choking effect. To overcome 80 this difficulty, a belt 28 is provided passing through keepers or loops 29 on the suit, so that the belt is maintained in proper place. A strap 30 is secured at one end to the back portion of the belt, and is adapted to be 85 passed between the wearer's legs and secured to the front portion of the belt by means of a buckle or other suitable device 31. This strap will hold the belt and therefore the body portion of the suit in proper 90 position and eliminate the discomfort and possible danger just pointed out.

Owing to the possible difficulty of drying a damped float and the impossibility of using same independently of the whole suit, 95 it may be found desirable to locate the float outside the garment, as shown in Fig. 6. The float will be in the form of a detachable and separately wearable vest 33 provided with a waterproof cover, and be preferably 100 fastened up the front and secured to the suit by any suitable fastening device 34 coöperating with a strap 35 fixed to the back of the suit, so that the buoyant vest will be normally a part of the suit. The strap 30 will 105 preferably be attached to the vest at the back, and the fastening device 31 at the front, so as to be available whether the entire suit or only the vest is worn.

It is obvious that since the suit is entirely 110 waterproof, it will be substantially air tight, and that therefore any air or moisture confined in the suit when it is put on would be retained. Such a condition would be a serious disadvantage and might even prove a 115 menace to the safety of the wearer, as the perspiration induced by swimming would dampen the interior of the suit and the wearer's clothes, so that if the water was at all cold, a chill would certainly result when the wearer became exhausted. Furthermore, the lack of ventilation would be 120 decidedly uncomfortable, and if air was imprisoned in the suit would have the effect of rendering the suit unwieldy. To overcome 125 this, air outlet valves 32 are provided in each shoulder of the suit to provide a vent for air and body moisture. These valves may be of any suitable design, which will open automatically for the escape of air, but 130

will normally remain closed to prevent the entrance of water.

It will be understood that any suitable material may be used in the manufacture of the suit, but it is preferred to use sheet rubber or rubber impregnated fabric having a suitable warm lining, so that a person wearing the suit who has not had opportunity to put on other clothing will be protected from the cold. It will also be understood that wherever desirable, clasps, straps or draw strings may be used to replace the elastic bands, or vice versa, without departing from the spirit of the invention, and that all such changes and minor modifications which constitute mechanical equivalents, while not specifically described, are held to form a part of the invention and be included therein.

Having thus described my invention, what 20 I claim is:—

In combination in a life saving suit, a one-piece garment completely covering the wearer with the exception of the face, a vest filled with buoyant material extending from 25 the neck to waist and normally attached to the garment, means securing the vest to the garment at the back of the neck, a strap attached to the back of the vest and passing between the garment legs to the vest front 30 arranged to adjust the garment to the wearer's body independently of the vest.

In witness whereof, I have hereunto set my hand, in the presence of two witnesses.

JOHN HUNTER CASSIDY.
